UNITED STATES PATENT OFFICE

2,435,409

COOLING ELECTRIC LAMPS

Kenneth Frederick Rushton, Bedmond, near
Watford, EnglandApplication March 13, 1945, Serial No. 582,443
In Great Britain May 13, 1943Section 1, Public Law 690, August 8, 1946
Patent expires August 16, 1963

2 Claims. (Cl. 240—47)

1

This invention relates to an improved holder for electric light bulbs and its object is to provide a lampholder having cooling means for the avoidance of over-heating of the bulb-holder. Quite an appreciable amount of the energy supplied to an electric lamp is given off in the form of heat, some of which reaches the lamp cap and socket, and further heat is developed at the socket contact or contacts owing to "contact resistance." The effects of such heat, whatever its source, are, in the main, harmful: it gives rise to softening of the lead contact or contacts on the lamp cap, also to weakening of the contact springs and burning out of flexible leads when such are used to convey current to the lamp.

The invention, which is applicable to all sorts of lampholders, is particularly well suited for use with low voltage electric lighting systems (as used, for instance, on motor vehicles, in air-raid shelters and in small dwellings): it is not, however, restricted to such use.

The main object of the invention is to provide a self-contained electric lamp holder capable of storing a large bulk of liquid coolant. Another object of the invention is to provide an electric lamp holder in which the place at which connection is made between conductor means in the lamp holder and exterior cables leading to a source of electric current are readily accessible from the exterior of the apparatus, instead of connection with the external circuit having to be made in the interior of the lamp holder as in constructions known hitherto. A further object of the invention is to provide a self-contained liquid cooled electric lamp holder which is especially suitable for supporting an electric lamp bulb of single pole type.

Further features of this invention will be described with reference to a particular embodiment thereof, depicted in the accompanying drawing. Figure 1 shows the device in axial section and Figure 2 is a transverse section (sectional plan view) taken on line II—II of Figure 1.

The lampholder as illustrated is of the bayonet catch type, the socket 1 having the usual angular slots 2, to receive pins 3 projecting from the cap 4 of the lamp bulb 5. The lamp, being of the "single pole" type, has a centre contact 6 for establishing connection with the "live" side of the current supply (battery or mains) and the usual earthed return is effected through the cap 4 and socket 1.

The said socket is fixed in one end of a tubular member 7 extending axially through a cylin-

2

drical tank-like container 8, adapted to hold the liquid coolant, the approximate surface level of which is indicated by the reference 9. The joints between the tube 7 and the container 8 must, of course, be made liquid-tight: this can be done in any known and convenient way as, for instance, by threading the ends of the said tube and providing packing washers 10 and nuts 11 to seal the joints. One of the nuts 11 is locked by a lock ring 12, the other by an internally threaded cap member 13. This latter, which may be made either of conducting or of insulating material, has an open bore 14 to admit current supply wires 15 (shown as a twin flexible). A ring or bail 16, engaged in the cap 13, affords means for suspending the device from a ceiling or the like, in a vertical position (that is to say, with the axis of the tube 7 vertical).

The centre contact 6 of the lamp 5 receives current through a conductor rod 17 extending axially through the tube 7 and supported therein by means of insulating blocks 18 and 19. One of the supply wires 15 (namely, the "live" wire) is electrically connected to the rod 17, the other ("neutral" or earthed) supply wire being connected to the tube 7 which, of course, is in electrical contact with the socket 1. Preferably, the said rod is itself constituted as a yielding contact for the centre of the socket: to this end it is made axially slidable in the insulating blocks 18 and 19 and is pressed against the lamp contact by a spring 20 interposed between the insulator 18 and a collar 21 fixed on the said rod, the downward movement of which is limited by a preferably adjustable stop collar 22, co-acting with the insulator 19. The insulator 18 bears against an annular abutment 23 within the tube 7 and is thereby prevented from receding further into the said tube under pressure exerted by the spring 20. The insulator 19 may also be located positively in the tube 7 but in the illustrated embodiment it is assumed to have been forced tightly into the said tube.

The reference numeral 24 designates the normal filling orifice through which the liquid coolant—preferably a suitable oil—can be introduced into the container 8. As a closure for this orifice a screw plug 25 (with packing washer 26) is provided but in order to permit air to leave or to enter the container, under the influence of thermal expansion and contraction, the said plug is pierced by an air vent 27. These filling and venting provisions are effective so long as the device as a whole is suspended in the vertical position (as it appears in Figure 1 of the

drawing). In order, however, to provide for horizontal or nearly horizontal mounting of the device a second orifice 28, closed by a screw plug 29 (with packing washer 30) is arranged in the side wall of the container. Since, with the device suspended vertically, the surface level of the liquid coolant is above the level of the orifice 28, the screw plug 29 is not vented but it is made interchangeable with the plug 25, so that the two plugs can be mutually transposed when the said device is to be supported horizontally (i. e. with the axis of the tube 7 horizontal). Obviously the interchangeable plugs can be manipulated to permit the device to be held obliquely at any desired angle of inclination.

A preferred way of adapting the device for horizontal or oblique mounting includes replacing the fittings 13 and 16 by a bracket or equivalent member secured to the same end of the tube 7 (the top end in Figure 1). For instance, a flanged tubular fitting may be screwed directly on to the said tube in place of the cap 13, the flange being holed so that it can be fixed by screws or the like to a vertical or inclined surface. Alternatively, the "top" end of the device may terminate in an electric plug connection of the "bayonet" or the "Edison screw" type capable of being engaged in a corresponding standard socket, whether the latter be of the cord-grip (suspension) pattern or of the "batten" (wall fixing) type.

The locknut 12, at the "bottom" end of the device may serve for the attachment of a shade or reflector for the lamp 5 or, if the protruding threaded end of the tube 7 be long enough, an additional ring nut may be used to function as a shade ring.

The cooled lampholder herein described is susceptible of various modifications in respect of its constructional details without departure from the essential features of the invention. Thus, in the case of double-pole systems the conductor rod 17 with the spring 20 and collars 21, 22 will be duplicated and the two supply wires 45 will be respectively connected to the two rods (instead of one wire being connected to the tube 17). The spacing of the two rods will, of course, be adapted to the spacing of the cap contacts in a double pole lamp. The showing of electrical connection in the top part of Figure 1 is purely diagrammatic: in practice the usual screw or other clamping connections will be used. Again, the tube 17 could be soldered or welded to the container which latter need not necessarily be cylindrical but could be of any desired shape and could, in suitable circumstances, serve as a reflector for the

lamp. Finally, cap fittings could be used instead of the closure plugs 26, 29.

I claim:

1. A self-contained liquid cooled electric lamp-holder for supporting an electric lamp bulb with a single pole cap, comprising a cylindrical container for liquid coolant, a tube passing centrally and longitudinally through said container with the opposite ends of the tube projecting beyond the ends of the container, apertured insulating blocks at the ends of the tube, an electric lamp socket for the tube and disposed on the outside of the insulating block at one end of the tube, a central conductor rod guided axially by the apertures in the insulating blocks, stop means on the rod to cooperate with one of said blocks for limiting axial movement thereof, spring means positioned between the end of the rod and the other of said insulating blocks for urging the conductor rod into the lamp socket to maintain resilient contact with the central single pole contact of the cap of an electric lamp bulb when the bulb cap is secured within the socket, and means for suspending the lamp holder in a vertical position, said means being connected to the end of the tube remote from that housing the socket.

2. A self-contained liquid-cooled electric lamp-holder for supporting an electric lamp bulb with a single pole cap, comprising a container for a liquid coolant, a tube extending through an entire dimension of said container, an electric lamp socket mounted at one end of said tube, insulating means mounted in said tube, a rigid conductor guided by said insulating means and axially slideable within said tube, and carrying collar means adjacent either end, and spring means co-acting with one of said insulating means and one of said collar means for urging the said rod against the single pole of an electric lamp cap inserted in said socket, the other of said collar means co-acting with the other of said insulating means to limit the action of said spring means.
